Primary Examiner — Marissa J Cash*(74) Attorney, Agent, or Firm* — Mintz Levin Cohn Ferris Glovsky and Popeo, P.C.(57) **CLAIM**

The ornamental design for a case, as shown and described.

DESCRIPTION

FIG. 1 is a front, top, and right side perspective view of a case showing our new design;

FIG. 2 is a rear, top, and right side perspective view thereof;

FIG. 3 is a right side view thereof;

FIG. 4 is left side view thereof;

FIG. 5 is a front view thereof;

FIG. 6 is a rear view thereof;

FIG. 7 is a top view thereof; and,

FIG. 8 is a bottom view thereof.

The dash-dash broken lines illustrate portions of the case that form no part of the claimed design.
